Geo. P. Kimmel, Attorney

UNITED STATES PATENT OFFICE.

MAURICE J. HOFFENBERG, OF NEW HAVEN, CONNECTICUT.

SKATE-FASTENER.

1,398,857.

Specification of Letters Patent. Patented Nov. 29, 1921.

Application filed January 4, 1921. Serial No. 434,916.

To all whom it may concern:

Be it known that I, MAURICE J. HOFFENBERG, a citizen of the United States, residing at New Haven, in the county of New Haven and State of Connecticut, have invented 5 certain new and useful Improvements in a Skate-Fastener, of which the following is a specification.

This invention relates to skate strap fasteners.

The object of the invention is to provide a simple and efficient device of this character which may be easily and quickly actuated for tightening the strap and readily 15 disengaged when it is desired to remove the skate.

Another object of the invention is to provide a fastener of this character which may be constructed with a minimum amount of 20 metal and yet be equally efficient as those of more expensive character.

With these and other objects in view, the invention consists in certain novel features of construction as hereinafter shown and described and specifically pointed out in the 25 claims.

In the accompanying drawing:

Figure 1 represents a side elevation of a 30 skate with this improved fastener shown applied, parts of the skate being broken out for convenience in illustration.

Fig. 2 is a detail longitudinal section taken on the line 2-2 of Fig. 1, and,

Fig. 3 is a detail perspective view of the 35 fastener detached.

In the embodiment illustrated, a roller skate S of ordinary construction is shown having the usual attaching straps A and B secured to opposite sides of the heel cap H.

The fastener constituting this invention is 40 in the form of an elongated metal plate 1 having a loop 2 extending transversely across one end thereof and in the same plane as the body portion. At the other end of the plate or body 1 is arranged another 45 transversely disposed loop 3 which is bent at an angle to the body 1 of the plate with a rounded portion 4 formed at the junction of said loop with said plate so as to adapt 50 the latter to conform to the shape of the ankle of the wearer when applied. Projecting at right angles from the opposed side edges of plate 1 in a direction opposite to the loop 3 and adjacent thereto are two 55 lugs 5 which are positioned out of alinement

with each other and are designed for a purpose presently to be described.

Plate 1 is provided near its other end adjacent loop 2 with a tongue 6 made integral with the plate 1 and projecting from one side 60 edge thereof on the face opposite to that which carries the lugs 5. The free end of the tongue 6 is bent laterally inward toward the plate 1 to assist in holding the strap A in place when folded as shown in 65 Fig. 2. This arrangement of the tongue provides for the slipping of the strap transversely thereunder for insertion or removal thereof avoiding the necessity of threading the strap through a keeper.

In the use of this fastener the straps A and B are secured to the loops 2 and 3 of the plate 1 which connect said straps and forms a loop for the passage of the foot of the wearer when applying the skate. After the 70 foot has been inserted through this loop so formed the plate 1 is thrown endwise into the position shown in Fig. 2 thereby taking up the slack in the strap and tightly fitting it around the ankle of the user. When the 75 buckle or fastener is so disposed the strap A is held between the tongue 6 and the plate 1 while strap B on the opposed face of said plate is held against lateral movement by the lugs 5 on opposite sides thereof. To 80 release the fastener all that is necessary is to move it transversely to disengage the strap B from under the tongue 6 and the fastener may then be swung outwardly enlarging the loop sufficiently to permit the 85 user's foot to be withdrawn.

The preferred embodiment of the invention is disclosed in the drawings and set forth in the specification, but it will be understood that any modifications within the 90 scope of the claimed invention may be made in the construction without departing from the principle of the invention or sacrificing any of its advantages.

What I claim is:

1. A skate strap fastener comprising a plate having attaching loops at its ends and provided adjacent one end on one side edge with an inturned transversely arranged tongue overlying and spaced from one face 105 of the plate, and strap engaging means adjacent the other end of said plate.

2. A skate strap fastener comprising a plate having attaching loops at its ends and provided adjacent one end on one side edge 110

with an inturned tongue overlying and spaced from one face of the plate, with its free end turned toward said plate, and strap engaging lugs carried by opposed side edges of said plate adjacent its other end on the face opposite to that carrying the tongue.

3. A skate strap fastener comprising a plate having attaching loops at its ends and provided adjacent one end on one side edge 10 with an inturned tongue overlying and spaced from one face of the plate, strap engaging lugs carried by opposed side edges of said plate adjacent its other end on the face opposite to that carrying the tongue, 15 said lugs being out of transverse alinement.

4. A skate strap fastener comprising a plate having attaching loops at its ends and provided adjacent one end on one side edge with an inturned tongue overlying and 20 spaced from one face of the plate, strap engaging lugs carried by opposed side edges of said plate adjacent its other end on the face opposite to that carrying the tongue, said lugs being out of transverse alinement and 25 bent slightly inward to engage opposite side

edges of a strap and hold the fastener engaged therewith.

5. A skate strap fastener comprising a plate having attaching loops at its ends and provided adjacent one end on one side edge 30 with an inturned tongue overlying and spaced from one face of the plate, strap engaging lugs carried by opposed side edges of said plate adjacent its other end on the face opposite to that carrying the tongue, said 35 lugs being out of transverse alinement and bent slightly inward to engage opposite side edges of a strap and hold the fastener engaged therewith, one end of said plate being bent facewise. 40

6. A skate strap fastener comprising a plate having attaching loops at its ends and provided adjacent one end on one side edge with an inturned transversely arranged tongue overlying and spaced from one face 45 of the plate, and strap engaging means adjacent the other end of said plate, one end of said plate being bent facewise.

In testimony whereof I affix my signature.
MAURICE J. HOFFENBERG.
